(57) **CLAIM**

The ornamental design for an electric connection terminal, as shown and described.

DESCRIPTION

FIG. 1 is front view of an electric connection terminal showing my new design;

FIG. 2 is a rear view thereof;

FIG. 3 is a left side view thereof;

FIG. 4 is a top plan view thereof;

FIG. 5 is a front perspective view thereof;

FIG. 6 is a rear perspective view thereof;

FIG. 7 is an end view thereof taken along the line 7-7 of FIG. 1;

FIG. 8 is a reference cross sectional view thereof showing a condition in use; and,

FIG. 9 is a reference disassembled perspective view thereof showing a condition in use.

A right side view and a bottom view are omitted because the right side view is symmetrical to the left side view and the bottom view is symmetrical to the top plan view.

The broken lines in drawings are directed to environment and form no part of the claimed design.
